UNITED STATES PATENT OFFICE.

P. J. LEONARD DE RACHE, OF NEW YORK, N. Y.

FIRE-PROOF CEILING.

SPECIFICATION forming part of Letters Patent No. 281,467, dated July 17, 1883.

Application filed May 10, 1883. (No model.)

To all whom it may concern:

Be it known that I, P. J. LEONARD DE RACHE, of the city, county, and State of New York, have invented a new and useful Improvement in Fire-Proof Ceilings, of which the following is a full, clear, and exact description.

Reference is to be had to the accompanying drawings, forming a part of this specification, in which similar letters indicate corresponding parts in all the figures.

Figure 1 is a plan view of a portion of a floor above a ceiling to which my improvement has been applied, parts being broken away. Fig. 15 2 is a sectional side elevation of the same taken through the line *x x*, Fig. 1. Fig. 3 is a sectional end elevation of the same taken through the line *y y*, Fig. 2.

The object of this invention is to promote 20 security in the construction of fire-proof ceilings.

The invention consists in a fire-proof ceiling constructed with ceiling-tiles supported from the joists by hangers, and supporting the facing-tiles placed against the sides of the joists and the top tiles placed between the upper parts of the joists, which top tiles and the tops of the joists are covered by a layer of cement, as will be hereinafter fully described.

30 A represents the ordinary joists of a building.

B are hangers to support the ceiling-tiles C. The hangers B are formed of iron bars bent at the center, so that the arms of the said bars will be parallel with each other, the bends being so made as to form eyes to receive the nails or spikes that fasten the said hangers B to the joists A. The ends of the arms of the hangers B are bent outward or from each other 40 at right angles, to form hooks to receive and support the ceiling-tiles C, the adjacent edges of which are recessed to receive the shanks of the hangers B, and the lower sides of which are recessed to a depth equal to the thickness 45 of the bars of which the hangers are made, so that the lower surface of the hooks of the said hangers B will be flush with the lower surface of the said ceiling-tiles C.

Against the sides of the joists A are placed facing-tiles D, the lower edges of which rest 50 upon the ceiling-tiles C, as shown in Figs. 2 and 3. The adjacent edges of the facing-tiles D are recessed to receive and fit against the hangers B, as shown in Fig. 2. Upon the upper edges of the facing-tiles D rest the lower sides of the ends of the top or arched tiles E, the said facing-tiles D being made of such a breadth that the upper surfaces of the said top tiles E will be flush with the upper edges of the joists A, as shown in Figs. 2 and 3. The 60 upper edges of the joists A and the tops of the tiles E are covered with a layer, F, of cement, upon which the floor-planks G are laid, and through which the said planks are nailed to the joists A; or the planks G can be laid, if 65 desired, upon strips of timber laid upon the cement layer F. By this construction the joists A will be entirely incased in fire-proof material, and thus fully protected from fire.

Having thus fully described my invention, I 70 claim as new and desire to secure by Letters Patent—

1. A fire-proof ceiling constructed substantially as herein shown and described, and consisting of the ceiling-tiles supported from the 75 joists by hangers, and supporting the facing-tiles and the top tiles, and the layer of cement covering the joists and the top tiles, as set forth.

2. In a fire-proof ceiling, the combination, 80 with the joists A and the ceiling-tiles C, of the hangers B and their fastening-spikes, substantially as herein shown and described, whereby the said tiles will be firmly supported, as set forth.

3. In the fire-proof ceiling, the combination, 85 with the joists A, the hangers B, and the ceiling-tiles C, of the facing-tiles D and the top tiles, E, substantially as herein shown and described, whereby the said facing-tiles and top tiles are supported by the ceiling-tiles and their hangers, as set forth.

P. J. LEONARD DE RACHE.
